THE NORRIS PETERS CO., PHOTO-LITHO., WASHINGTON, D. C.

UNITED STATES PATENT OFFICE.

EARL L. PANGBORN AND HENRY W. NIERMEYER, OF INDIANAPOLIS, INDIANA.

TROLLEY-REPLACER.

1,276,564.

Specification of Letters Patent. Patented Aug. 20, 1918.

Application filed May 7, 1917. Serial No. 166,963.

To all whom it may concern:

Be it known that we, EARL L. PANGBORN and HENRY W. NIERMEYER, citizens of the United States, residing at Indianapolis, in the county of Marion and State of Indiana, have invented certain new and useful Improvements in Trolley-Replacers, of which the following is a specification.

This invention relates to improvements in mechanism for automatically replacing trolley wheels which have become displaced from the wires from which they take the electric current, and the object of the invention is to provide a simple and durable device which will be actuated by the displaced wire.

We accomplish the objects of the invention by the mechanism illustrated in the accompanying drawings, in which—

20 Figure 1 is a view in side elevation of a trolley wheel and wire to which wheel our invention is applied and is shown in full lines set ready to replace the wheel, and in dotted lines in raised position after the wire 25 has been replaced. Fig. 2 is a cross section of the wire looking at the wheel and its mechanism in elevation in the direction shown by the arrow 2, in Fig. 1, and Fig. 3 is a view of the inner side of the ratchet 30 wheel. Fig. 4 is a section on the line 4—4 of Fig. 1.

Like characters of reference indicate like parts throughout the several views of the drawings.

35 The trolley wire 4, wheel 5 and harp 6, supporting the wheel are of any usual and suitable construction. In axial alinement with the axis of rotation of the wheel, are two extensions 7 and 8 capable of a rocking 40 adjustment through an arc of approximately 180°. These terminate at their outer ends with arms 9, at right angles to said extensions, and these in turn have inturned triangular frames 10, the inner angles of which 45 terminate opposite the respective adjacent flanges of the wheel 5. These arms are carried normally in approximately horizontal positions pointing in opposite directions to the travel of the car, and may be correspondingly set as the direction of travel is changed.

50 Springs 11 have one end of each fastened to the harp and are wrapped around the respective extensions 7 and 8 and have their outer ends fastened to the said extensions. 55 These springs are set to normally raise the arms, whether set toward the front or rear,

to a vertical position shown by the dotted lines in Figs. 1 and 2. The two arms are rigidly united to cause them to move together, preferably by forming the extensions 60 7 and 8 from a single rod which passes through the trolley wheel axle. To make the arms ride freely under the overhead work which holds the trolley wire, particularly at curves, when the arms are in their raised positions we provide the arched ribs 65 12 on one side and curve the end 13 of each arm on the other side, as shown.

Mounted in a fixed manner on the extension 8 is a wheel 14, having a double series 70 of diametrically opposite ratchet teeth (see Fig. 3) on the side next to the harp, and a pair of radial pins 15, one at the lower end of each series of teeth.

Fastened rigidly to the harp is a bar 16, 75 the upper and lower ends of which terminate approximately even with the outer adjacent rim of the trolley wheel. To the upper end of this bar the outwardly and downwardly sloping cross head 17 of a plate is hinged. 80 At the outer end of this head an upwardly projected stop-lug 18 is formed. Depending from the head is an integral stem 19, having a single tooth 20, in its outer edge to engage with the ratchet teeth of one of the series 85 of teeth on the wheel 14—the engaged series depending upon which way the arms are turned, as, toward the front or rear. A yielding engagement is secured by a spring 21 between the stem 19 and bar 16, which 90 normally presses the stem toward the ratchet wheel. At the inner side of the lower end of the stem 19 is a perforated lug 22, which loosely receives the reduced and upwardly bent end of a lever 23. The lever 23 is pivoted to the lower end of the bar 16. Its 95 opposite long arm extends across the wheel 4, and is then bent upwardly and extends across a chord of the wheel, and is then bent in an outward and downwardly oblique direction analogous to but in reverse to the sloping cross head 17. The end of the long arm of the lever is bent up to form the stop 18'. The function of the two oppositely oblique members terminating with stops 18 100 and 18' is to catch the wire 4 when the wheel 5 leaves it by accident. The weight of the wire on the cross head 17 and the pressure of the latter against the wire causes the plate to swing about its pivotal attachment to the bar 16, thereby withdrawing the tooth 20 105 from its engagement with the ratchets of

110

the wheel. This releases the arms which move to vertical position by the action of the springs 11, bringing their inturned triangular frames 10 against the wire and sliding it back into the groove of the trolley wheel. The connection of the lever 23 with the plate will operate the latter to withdraw tooth 20 and release the arms in like manner when the wire contacts it.

10 When the pressure of the wire is removed from cross head 17 or the oblique end of lever 23 by the action of the arm extensions 10, the spring 21 moves the stem 19 out causing its tooth to reengage the ratchets 15 if any are in its path, and to keep this from prematurely happening we provide a device for locking the stem in its remote position from the wheel. This comprises a lever 25, pivoted at one end to the bar 16, and having its other end contacting the wheel periphery between and in the path of the pins 15, and adapted to be oscillated in one direction by one or the other of said pins, depending upon which way the arms 20 are horizontally set. Oscillation in the other direction is by the action of a pin 26 seated in the stem 19 and entering a cam-groove 27 in the side of the lever next to the stem, in the shape of a trapezoid, with rounded corners and the shortest parallel side toward the outer end of the lever. The lever is suitably expanded to accommodate the cam-groove. A normal horizontal position of the lever is insured by the action of a spring 32, which is attached to the bar 16, and bears 25 against the squared end of the lever. The adjacent corners of the lever are carried out to form cams 29, to increase the end bearing and certainty of action of the spring in 30 turning the lever to horizontal position.

40 The operation of our device is as follows: Assuming the parts to be as shown by the full lines of the drawings and the wheel to be off the trolley wire as shown by the position of the latter in dotted lines, Fig. 2, the pressure of the wire against head 17 swings the stem 19 inwardly disengaging tooth 20 from the ratchets of wheel 14. This moves the pin 26 from the position in its cam-groove 27 shown in Fig. 2, to a position at 45 the middle of the parallel inner portion, which will hold the stem with its tooth 20 away from the wheel 14. The arms are 50 swung up to the positions shown in dotted lines, replacing the wire in the trolley wheel, by the action of the springs 11, and the arms will remain in that elevated position until, 55 by the forward travel of the car, they come in contact with one of the guy-wires or other 60 part of the overhead work attached to the trolley wire 4. Contact with the latter will force the arms back to their horizontal position, where they will be held by engagement of tooth 20 in the ratchets of wheel 14. The 65 release of the stem from lever 23, by the

contact of pin 15 on wheel 14, with the end of the lever, moving the lever so its cam-groove returns pin 26 to the position shown in Fig. 2.

When the direction of travel of the car is 70 reversed the arms will operate in like manner in the opposite quadrant of the 180° arc indicated by the dotted lines in Fig. 1.

Instead of forming the rods 7 and 8 from a one-piece member, it is often desirable to 75 separately unite them. We, therefore, do not wish to be understood as confining ourselves to the one piece member.

In the modification shown in Fig. 4 the rods 7 and 8 are joined at the middle of the 80 axle 30 by a tongue and groove joint. The inner ends of the springs 11 are fastened to collars 31, which are held by set screws 32 from the harp, which screws also hold the axle in fixed position. Longitudinal separation of the rods is prevented by pins 33. By disengaging the screws 32 from the collars 31, the rods 7 and 8 can be withdrawn, and by further outward movement of the set screws the axle 30 and trolley wheel may 90 also be removed.

While we have described our invention with more or less minuteness as regards details of construction and arrangement and as being embodied in certain precise forms, we 95 do not desire to be limited thereto unduly or any more than is pointed out in the claims. On the contrary, we contemplate all proper changes in form, construction, and arrangement, the omission of immaterial 100 elements and the substitution of equivalents as circumstances may suggest or as necessity may render expedient.

We claim—

1. The combination, with a trolley wheel 105 and harp, of a two-part rod passing through the axis of rotation of the wheel and each part terminating at its outer end in a right angle arm extending parallel with the trolley wheel, oblique members arranged on and 110 sloping from said arms to the periphery of the trolley wheel, spring means to move the arms substantially to a vertical position when the springs are unrestrained, automatic means to lock the arms when they are 115 in a substantially horizontal position, and automatic means actuated by the wire when the trolley is off of it, to unlock the arms.

2. The combination, with a trolley wheel 120 and harp, of a two-part rod passing through the axis of rotation of the wheel and each part terminating at its outer end in a right angle arm extending parallel with the trolley wheel, oblique members arranged on and 125 sloping from said arms to the periphery of the trolley wheel, automatic means to lock the arms in a substantially horizontal position when they are moved thereto by contact with the overhead work supporting the trolley wire, means actuated by the wire 130

when the trolley is off to unlock the arms and spring means to raise the arms to a substantially vertical position when unlocked.

3. The combination, with a trolley wheel and harp, of a two-part rod passing through the axis of rotation of the wheel and each part terminating at its outer end in a right angle arm extending parallel with the trolley wheel, oblique members arranged on and sloping from said arms to the periphery of the trolley wheel, automatic means comprising a ratchet wheel and pawl-lever to lock the arms in a substantially horizontal position when they are moved thereto by contact with the overhead work supporting the trolley-wire, means actuated by the wire when the trolley is off to move the pawl-lever to unlock the arms, and spring means to raise the arms to a substantially vertical position when unlocked.
4. The combination, with a trolley wheel and harp, of a two-part rod passing through the axis of rotation of the wheel and each part terminating at its outer end in a right angle arm extending parallel with the trolley wheel, oblique members arranged on and sloping from said arms to the periphery of the trolley wheel, automatic means comprising a ratchet wheel and pawl-lever to lock the arms in a substantially horizontal position when they are moved thereto by contact with the overhead work supporting the trolley-wire, means actuated by the wire when the trolley is off to move the pawl-lever to unlock the arms, and spring means to raise the arms to a substantially vertical position when unlocked.
5. The combination, with a trolley wheel and harp, of a two-part rod passing through the axis of rotation of the wheel and each part terminating at its outer end in a right angle arm extending parallel with the trolley wheel, oblique members arranged on and sloping from said arms to the periphery of the trolley wheel, automatic means comprising a ratchet wheel and pawl-lever to lock the arms in a substantially horizontal position when they are moved thereto by contact with the overhead work supporting the trolley-wire, means actuated by the wire when the trolley is off to move the pawl-lever to unlock the arms, and spring means to raise the arms to a substantially vertical position when unlocked.
6. The combination, with a trolley wheel and harp, of a pair of arms substantially at right angles to and swinging on the axis of rotation of the wheel, the lengths of said arms being greater than the radius of the wheel, said arms having members on their sides next to the wheel sloping toward the latter and having curved portions at right angles to the sloping members, means to lock the arms when they are lowered by contact with the overhead work supporting the wire, means on both sides of the trolley wheel to unlock the arms by contact with the wire when the wheel is off the wire, and automatic means to raise the arms when unlocked.
7. The combination of a harp, an axle having a longitudinal bore, a trolley wheel loosely mounted on the axle, a pair of arms each having a rod-member which rod-members are assembled from opposite ends in the bore of the axle, collars on the axle, set screws from the harp holding the collars, interlocking means at the meeting ends of the rod-members and means on the rod members to prevent their longitudinal movement through the collars.

In witness whereof we have hereunto set our hands and seals at Indianapolis, Indiana, this 18th day of April, A. D. one thousand nine hundred and seventeen.
